CAPPING MACHINE

Filed June 24, 1931

Fig. 1.

Fig. 2.

A technical line drawing of a garment pattern, likely a vest or jacket front. The pattern includes a notched collar and a zipper area. A zipper track is marked with a dashed line, and a zipper pull is indicated by a small circle labeled '30'. The zipper is shown partially inserted into a zipper tape. The pattern is labeled with '29' at the bottom of the zipper area and '7' at the bottom right corner. The drawing is signed 'Fig. 3.' in the bottom left corner.

UNITED STATES PATENT OFFICE

LAWRENCE PIUS SINZ, OF HUNTINGTON PARK, CALIFORNIA, ASSIGNOR TO CROWN CORK & SEAL COMPANY, INC., OF BALTIMORE, MARYLAND, A CORPORATION OF NEW YORK

CAPPING MACHINE

Application filed June 24, 1931. Serial No. 546,589.

The present invention relates to capping machines and has particular reference to means for controlling the feed of caps to the cap applying mechanism. While the invention has a general application, it constitutes particularly an improvement over the mechanism shown in U. S. Patent No. 1,260,964, issued to Amos Calleson, March 26, 1918, and the invention has been shown in the accompanying drawing as applied to the machine of the patent in substitution for the feed control mechanism therein embodied.

In the drawing:

Figure 1 is an elevation of the lower end 15 of the capping head and its appurtenances.

Figure 2 is an elevation of the structure shown in Figure 1, partly in section, as seen from the right of that figure, and

Figure 3 is an enlarged view substantially 20 on the sectional line 3—3 of Figure 1.

Referring to the drawing, reference numeral 5 indicates generally the vertically reciprocable head of the sealing machine, beneath which crown caps are adapted to be delivered by means of chutes 6 and 7. As shown, the outer wall of each chute is composed of spaced strips which form trackways for the caps and between which, at the delivery end of the chutes, latch members are 30 projectable to engage and check the feed of the caps in the chutes.

Brackets 8 and 9 are secured to the chutes adjacent their delivery ends and constitute bearings for a rock shaft 10 which is journaled therein. Mounted on the rock shaft and oscillable relative thereto are a pair of latches 11 and 12, of identical construction. Latch 12 is shown in detail in Figure 3, and will be particularly described, it being understood that the description applies equally to latch 11.

Referring then to Figure 3, the latch comprises a hub portion 13, a nose 14, and a tail 15, the hub being provided with a bore which receives shaft 10. The hub portion is provided with an elongated radial slot 16 in which is engaged an abutment member in the form of a pin 17 having a threaded shank engaged in a tapped radial bore in shaft 10. Pin 17 prevents displacement of

the latch axially of the shaft, but permits its oscillation relative to the shaft between the limits wherein the ends of the slot are engaged by the pin. The latch is provided with a bore 18 parallel to shaft 10 in which is engaged the end of a torsion spring 19 which surrounds shaft 10, the other end of spring 19 being integral through the connecting portion 20 with one end of a section torsion spring 21 whose other end is engaged in a bore similar to bore 18 in latch 11. The connecting portion 20 of the two springs is engaged in an axially extending kerf formed in a lug 10' which projects radially of shaft 10 so that the adjacent ends of the spring are held against relative rotation to the shaft in either direction. Looking at Figure 3, the torsion springs tend to rotate the latches in a clockwise direction relative to the shaft, such tendency being limited by the abutment 70 of the pins with the ends of the slots, pin 17 being thus yieldably held in engagement with the end 16' of slot 16.

A crank arm 22 fixed to one end of shaft 10 is connected through a telescoping link 23 with a vertical rod 24 relative to which the head 5 is reciprocable. Link 23 comprises a lower cylinder portion 25 pivoted on the crank pin 22' and an upper piston portion 26 having a head 26' pivoted to the rod 24 by means of a pin 27', Figure 2. In Figures 1 and 2, the link is shown in extended relation, this relation being assumed when the head 5 is in its lowermost position. Upon upward movement of the head, abutment portions 25' and 26'' of the link portions come into abutment after a certain lost motion interval, whereupon shaft 10 is rocked through the intermediary of crank 22, positively oscillating the latches through the abutment pins which engage the slot ends in the manner shown in Figure 3. The noses 14 of the latches are thus moved from the full line position of Figure 3 in which they extend through the outer walls of the chute in position to engage caps therein to check the feed thereof to the dotted line position in which the noses release the caps for feed.

It will be noted from Figure 2 that the lower end of cylinder portion 25 is provided

with a vent 25" in order that telescoping movements of the link parts may not be impeded by compression or vacuum effects in the cylinder.

5 Fixed on shaft 10 at the opposite end from crank 22 is a crank arm 27 having fixed thereto a pin 28 which is connected by means of a tension spring 29 with a pin 30 projecting from a bracket element 31. Upon downward movement of head 5, abutment portions 25' and 26" eventually move apart allowing spring 29 to rock shaft 10 and thereby positively oscillate the latches through the intermediary of the torsion springs from 15 the dotted line position of Figure 3 to the full line position. When this latter position is reached, further rocking of the shaft is prevented by the engagement of a lug 32 formed on the hub 33 of crank arm 27 with a 20 foot portion of bracket 9. With the parts in this position, either of the latches may be oscillated through manual operation of the latch tails so that the associated chute may be cleared, the strength of the torsion springs 25 being less than that of spring 29 so that shaft 10 is not affected by the relative oscillation of the latches. The latches are provided with oil holes 11' and 12' so that they may be supplied with lubricant to ensure their free 30 movement relative to the shaft.

It will be understood that in actual practice nose 14, Figure 3, comes up beneath the leading cap in the chute, this cap having been omitted in order not to interfere with 35 the showing of the other parts.

The invention is capable of being embodied otherwise than as specifically shown and described herein, and accordingly it will be understood that I do not limit myself except as in the following claims.

I claim:

1. In a machine of the class described, a plurality of chutes arranged side by side and having apertures adjacent their delivery ends, a rock shaft adjacent and beneath the delivery ends of the chutes and extending transversely of the chutes, a plurality of latches on said rock shaft and oscillable relative thereto, said latches having nose portions adapted to extend through said chute apertures in checking relation to closure caps in the chutes and having tail portions manually operable to oscillate the latches independently of each other to move the latch noses out of checking relation to the caps, and connecting means between the shaft and latches whereby rocking of the shaft causes simultaneous oscillation of the latches.

2. In a machine of the class described, a plurality of chutes arranged side by side and having apertures adjacent their delivery ends, a plurality of latches oscillable beneath said chutes and having noses movable upon oscillation of the latches from a position in 65 which they extend through the chute aper-

tures to engage and check the feed of closure caps in the chute to a position in which they release the caps for feed, said latches being provided with bores aligned transversely of the chutes, a rock shaft extending through said bores and supporting the latches, cooperating abutment means on the shaft and latches whereby rocking movement of the shaft in one direction is imparted to the latches to move the latch noses simultaneously from cap engaging to cap releasing position, and spring means influencing the latches to cause engagement of said cooperating abutment means, said latches being manually oscillable independently of each other and of said shaft against the action of said spring means to move the latch noses from cap engaging to cap releasing position.

3. In a machine of the class described, a plurality of chutes arranged side by side and having apertures adjacent their delivery ends, a plurality of latches oscillable beneath said chutes and having noses movable upon oscillation of the latches from a position in which they extend through the chute apertures to engage and check the feed of closure caps in the chute to a position in which they release the caps for feed, said latches being provided with bores aligned transversely of the chutes, a rock shaft extending through said bores and supporting the latches, cooperating abutment means on the shaft and latches whereby rocking movement of the shaft in one direction is imparted to the latches to move the latch noses simultaneously from cap engaging to cap releasing position.

4. In a machine of the class described, a plurality of chutes arranged side by side and having apertures adjacent their delivery ends, a plurality of latches oscillable beneath said chutes and having noses movable upon oscillation of the latches from a position in which they extend through the chute apertures to engage and check the feed of closure caps in the chute to a position in which they release the caps for feed, said latches being provided with bores aligned transversely of the chutes, a rock shaft extending through said bores and supporting the latches, cooperating abutment means on the shaft and latches whereby rocking movement of the shaft in one direction is imparted to the latches to move the latch noses simultaneously from cap engaging to cap releasing position.

4. In a machine of the class described, a plurality of chutes arranged side by side and having apertures adjacent their delivery ends, a plurality of latches oscillable beneath said chutes and having noses movable upon oscillation of the latches from a position in which they extend through the chute apertures to engage and check the feed of closure caps in the chute to a position in which they release the caps for feed, said latches being provided with bores aligned transversely of the chutes, a rock shaft extending through said bores and supporting the latches, cooperating abutment means on the shaft and latches whereby rocking movement of the shaft in one direction is imparted to the latches to move the latch noses simultaneously from cap engaging to cap releasing position.

- ly from cap engaging to cap releasing position, and torsion springs surrounding the shaft with their ends respectively connected to the shaft and latches and acting to cause engagement of said cooperating abutment means, said latches being manually oscillable independently of each other and of said shaft against the action of said springs to move the latch noses from cap engaging to cap releasing position. 5 and check the feed of caps in the chute to a position in which it releases the caps for feed, a rock shaft extending transversely of the chute and through a bore provided in said latch, and spring means connecting the shaft 70 and latch for yieldingly transmitting rocking movement of the shaft to the latch to move the latch nose from cap releasing to cap engaging position, said latch being manually oscillable relative to the shaft against 75 the force of said spring means to move the latch nose from cap engaging to cap releasing position.
5. In a machine of the class described, a plurality of chutes arranged side by side and having apertures adjacent their delivery ends, a plurality of latches oscillable beneath 15 said chutes and having noses movable upon oscillation of the latches from a position in which they extend through the chute apertures to engage and check the feed of closure caps in the chute to a position in which they 20 release the caps for feed, said latches being provided with bores aligned transversely of the chutes, a rock shaft extending through said bores and supporting the latches, said latches having hubs provided with elongated 25 radial slots, abutment means on the shaft extending within the slots, and spring means interposed between the shaft and latches and influencing the latter to hold one end of their slots in abutment with their associated abut- 30 ment means, rocking of said shaft in one direction being simultaneously transmitted to the latches through the abutment means and slot ends to oscillate the latches and thereby move the latch noses from cap engaging to 35 cap releasing position, said latches being manually oscillable independently of each other and of said shaft against the action of said spring means to move the latch noses from cap engaging to cap releasing position. 40 6. In a machine of the class described, a pair of relatively reciprocable members, a rock shaft carried by one of said members, a crank on said rock shaft, a telescoping link embodying cooperating abutment means for 45 limiting its collapse, said link constituting a lost motion connection between said crank and the other of said members, spring means tending to rock said shaft in a direction to collapse said link, means limiting the rocking 50 of the shaft in such direction, relative movement of the two members in one direction causing eventual engagement of said abutment means and consequent rocking of said shaft against the action of said spring 55 means, the spring means acting to return the shaft upon relative movement of said members in the opposite direction, and cap feed control means operated by said shaft. 60 7. In a machine of the class described, a closure cap feeding chute having an aperture adjacent its delivery end, a latch oscillable beneath the delivery end of the chute and having a nose movable upon oscillation of the latch from a position in which it extends through the chute aperture to engage 65 and check the feed of caps in the chute to a position in which it releases the caps for feed, a rock shaft extending transversely of the chute and through a bore provided in said latch, and spring means connecting the shaft 70 and latch for yieldingly transmitting rocking movement of the shaft to the latch to move the latch nose from cap releasing to cap engaging position, said latch being manually oscillable relative to the shaft against 75 the force of said spring means to move the latch nose from cap engaging to cap releasing position. 80 8. In a machine of the class described, a closure cap feeding chute having an aperture adjacent its delivery end, a latch oscillable beneath the delivery end of the chute and having a nose movable upon oscillation of the latch from a position in which it extends through the chute aperture to engage 85 and check the feed of caps in the chute to a position in which it releases the caps for feed, a rock shaft extending transversely of the chute and through a bore provided in said latch, cooperating abutment means on the shaft and latch whereby rocking movement of the shaft in one direction is imparted to the latch to move the latch nose from cap engaging to cap releasing position, and spring 90 means influencing the latch to cause engagement of said cooperating abutment means, said latch being manually oscillable relative to the shaft against the force of said spring means to move the latch nose from cap engaging to cap releasing position. 95 9. In a machine of the class described, a closure cap feeding chute having an aperture adjacent its delivery end, a latch oscillable beneath the delivery end of the chute and having a nose movable upon oscillation of the latch from a position in which it extends through the chute aperture to engage 100 and check the feed of caps in the chute to a position in which it releases the caps for feed, a rock shaft extending transversely of the chute and through a bore provided in said latch, cooperating abutment means on the shaft and latch whereby rocking movement of the shaft in one direction is imparted to the latch to move the latch nose from cap engaging to cap releasing position, and spring 105 means influencing the latch to cause engagement of said cooperating abutment means, said latch being manually oscillable relative to the shaft against the force of said spring means to move the latch nose from cap engaging to cap releasing position. 110 10. Control means for the closure cap feed of capping machines, said means comprising a rock shaft, a latch having a hub portion traversed by said rock shaft, said hub being provided with an elongated radial slot, a pin on said rock shaft engaged in said slot, said latch being oscillable relative to the shaft be- 115 120 125 130

tween limit positions in which the pin engages the slot ends, and a spring interposed between the shaft and latch and normally yieldably holding one of the slot ends in engagement with said pin.

5 In testimony whereof, I have hereunto set my hand.
